TOY HOBBYHORSE VEHICLE

Laurie J. Campbell, Erie, Pa., assignor to Louis Marx & Co., Inc., New York, N.Y., a corporation of New York

Filed Jan. 17, 1963, Ser. No. 73,217

Term of patent 14 years

(Cl. D34—15)

FIG. 1.

FIG. 2.

FIG. 3.

FIG. 4.

FIG. 5.

FIG. 6.

FIG. 1 is a side elevational view of the right side of a toy hobbyhorse vehicle embodying my new design;

FIG. 2 is a side elevational view of the left side thereof;

FIG. 3 is a top plan view thereof;

FIG. 4 is a front elevational view thereof;

FIG. 5 is a rear elevational view thereof; and

FIG. 6 is a bottom plan view thereof.

I claim:

The ornamental design for a toy hobbyhorse vehicle, as shown.
